UNITED STATES PATENT OFFICE.

JAMES L. MCQUARRIE, OF MONTCLAIR, NEW JERSEY, ASSIGNOR TO WESTERN ELECTRIC COMPANY, INCORPORATED, OF NEW YORK, N. Y., A CORPORATION OF NEW YORK.

TELEPHONE SWITCHING APPARATUS.

1,376,893.

Specification of Letters Patent.

Patented May 3, 1921.

Application filed May 13, 1918. Serial No. 234,180.

To all whom it may concern:

Be it known that I, JAMES L. MCQUARRIE, a citizen of the United States, residing at Montclair, in the county of Essex, State of New Jersey, have invented certain new and useful Improvements in Telephone Switching Apparatus, of which the following is a full, clear, concise, and exact description.

This invention relates to automatic telephone exchange systems, and particularly to a novel arrangement in the construction and operation of the switching apparatus used therein for establishing conversational connections between subscribers' lines.

It is the customary practice in automatic telephone systems to arrange the subscribers' lines and the switches used for interconnecting the same in groups, each group and the subdivisions thereof being arbitrarily assigned a suitable numerical designation. Where all switches of a group, whether finders, selectors or connectors, are common to the use of all lines in one or more groups of lines, it is necessary to provide as many switches to serve a group of lines as is required to handle the largest number of simultaneous calls that is expected to arise in such group. Experience shows that in systems operating under the average traffic conditions, the maximum number of calls likely to appear in a group is about ten per cent. of the number of lines in the group.

Considering the type of selective switches generally used heretofore in automatic telephone systems in which the selectively controlled movable element, as the switch shaft, has fixed thereto and movable therewith elements, such as the contact brushes, which form an actual part of the conversational circuit established, it is seen that on the above assumed basis of traffic it becomes necessary to employ ten switches to serve a group of one hundred lines. When a call is initiated, one of the switches will be operated to its set position to extend the connection and will remain in this position until the conversation has been terminated. On the occurrence of a second call in the same group, one of the nine remaining switches is similarly operated and held in use to the exclusion of other lines during the conversational period, and hence where switches of this type are used the necessity

of employing ten switches to give a certain group of one hundred lines a proper grade of service, results not only from the fact that a switch must be held to the exclusive use of the calling line during the connecting period, but also from the more important fact that the switch must be maintained busy and non-available to other lines during the entire talking period. This is true since, as above stated, the switch after having performed its primary function of selecting the desired circuit must remain out of use during the talking period merely because the directly controlled movable part of the switch carries elements which are essential to the maintenance of the connection established.

In view of the foregoing, this invention has as its general object, the provision of a switch which may be directly operated to select the proper circuit in a desired numerical group, effect the necessary connections with such circuit, and thereupon restore immediately to its normal position where it again becomes available to all other lines in the group. By this means the busy period of the switch is greatly reduced with the result that the number of switches needed to afford a group of lines a given grade of service may likewise be reduced.

A feature of the invention consists in a novel arrangement of the contact bank whereby a plurality of incoming circuits are arranged to have a crossing or intersecting point with each of a plurality of outgoing circuits, together with means such as deposit members provided at each of the intersecting points, and which serve, when operated, to effect a connection between the particular incoming and outgoing circuits represented by such intersecting point.

A further feature resides in providing a directly controlled step-by-step switching mechanism which is adapted to be operated in several distinct movements to select and deposit a circuit connecting member at any desired crossing point in the bank.

Another feature relates to a step-by-step operated releasing mechanism which is effective to restore the circuit connecting members to normal when conversation ceases.

Other features will be made apparent from the following description.

In the drawings, Figure 1 is a top plan

view of a switch embodying this invention showing a portion of the contact bank, together with the switch operating mechanism; Fig. 2 is a side view of the switch, 5 certain parts being removed to afford a clearer understanding of the operation; Fig. 3 is a bottom plan view illustrating the releasing mechanism; Fig. 4 is an enlarged cross-sectional detail showing the relative arrangement of some of the operating 10 parts; Fig. 5 is an enlarged detail in perspective showing the manner of controlling the sliding bar which operates the plunger for depositing a contact making member; 15 and Fig. 6 is an enlarged view in perspective showing one of the deposit members and the circuit contact springs which it controls.

While the principle of this invention is 20 adapted to any class of automatic telephone switch it will be considered for the purpose of the present discussion as embodied in a selector switch, the function of which is to connect incoming trunks from finders or 25 other selectors to trunks outgoing in the proper direction to selector or connector switches.

Referring to the drawing, there is shown in Figs. 2, 3 and 6 the manner in which the 30 incoming and outgoing trunk circuits are arranged in the contact bank. There are ten incoming two-conductor trunk circuits 1, 1, arranged in a plane surface, and disposed along the arcs of concentric circles. Arranged in a plane immediately below that of trunks 1, 1 is a plurality of outgoing 35 two-conductor trunk circuits 2, 2. The trunks 2, 2 each extend radially toward the common center of the arcs of trunks 1, 1, 40 whereby each of the incoming trunks 1, 1 has an intersection or a crossing point with each of the outgoing trunks 2, 2. Preferably the outgoing trunks 2, 2 comprise a total of one hundred circuits, which may 45 be divided into ten groups of ten trunks each, each of the successive groups consisting of ten adjacent trunks 2, 2, and occupying a portion or sector of the contact bank. With this arrangement any one of 50 the ten incoming trunks 1, 1 has a crossing point with each of the trunks of ten groups of outgoing trunks 2, 2. Each of the incoming circuits 1, 1 is provided, at the points where it crosses the outgoing circuits 55 2, 2, with spring contact members 3 and 4. Likewise the outgoing trunks 2, 2 are provided at these points of crossing with contact springs 5 and 6. The springs 3, 4, 5 and 6 are firmly secured to an insulating 60 supporting plate 7 with their free ends extending upward into a position to coöperate with each other, as best seen in Figs. 2 and 6. Slidably mounted in plate 7 at the points of intersection are the deposit pins 8, 8. The pins 8 are provided with cam

members 9 having two graduated notches arranged to coöperate with the opposing curved ends of the innermost contact springs 3 and 4. When the pin 8 is in its normal upper position, springs 3 and 4 engage the lower notch in cam 9, whereby said springs are out of contact with springs 5 and 6. When, however, pin 8 is depressed and assumes its lower position with the upper notch thereof in engagement with springs 3 and 4 said springs are flexed into contact with outer springs 5 and 6 respectively. To economize in space, the springs 5 and 6 are arranged to be engaged by springs 3 or 4, as the case may be, 75 at two adjacent radial positions in the bank as shown in Fig. 2. In this way the springs 5 and 6 of one set may be common to two different trunk intersecting points.

A description will next be given of the 80 step - by - step impulse operated switching mechanism, which coöperates with the contact bank to first select a group of incoming and outgoing trunk intersecting points, then to select a single row of intersections of an 85 idle outgoing trunk with the incoming trunks, then to select the intersection of this chosen outgoing trunk with a particular one of the incoming trunks, and lastly to deposit the pin 8 at such intersection. 90 Rotatably mounted in the upper shelf 10 of supporting frame 29 is a gear member 11, provided at its upper end with gear teeth 12, and at its intermediate portion with an enlargement 14, around the periphery of which 95 gear teeth 13 are arranged. Interposed between the enlargement 14 and the upper surface of shelf 10 is a ratchet wheel 15 which is journaled for rotation about member 11 as a bearing, and which also serves 100 as a guide or stop to limit member 11 against downward movement. A nut 16 threaded on the lower end of member 11 retains the same against displacement in 105 the opposite vertical direction. Supported 110 on the upper surface of the enlargement 14, and journaled for rotation about gear member 11, is a combined plunger bar carriage 115 and gear member 17. A nut 18 screwed upon a threaded portion of member 11 holds carriage 17 in proper vertical alinement. The carriage 17 is in general of a circular shape, its largest portion being provided with peripheral teeth to form the ratchet wheel 19. Just below ratchet wheel 19, the 120 carriage 17 has its diameter considerably reduced, the reduced portion so formed being provided with gear teeth 20.

The carriage 17 is also provided with a 125 rectangular boss 21 which rises above the ratchet wheel 19, and is located to one side of the center thereof, Fig. 1. Boss 21 has extending longitudinally therethrough a rectangular slot or channel 22, in which there is slidably mounted a plunger carrying bar 130

23. A plunger 24 is mounted on the working end of bar 23, a bracket 25 serving as a guide therefor, while a coiled spring 26 acts to normally retain the plunger in the position 5 shown. On the other end of bar 23 is cut a series of teeth 27 which constantly engage the gear teeth 12 on member 11. A coiled spring 28, one end of which is attached to bar 23, and the other end to boss 21, exerts 10 its tension to hold the plunger bar in its normal innermost position, as seen in Figs. 1 and 2. By this arrangement when the carriage is held stationary with respect to the switch frame, and member 11 rotated about 15 its axis, the gear teeth 12 meshing with teeth 27 cause bar 23 to be thrust radially outward to carry plunger 24 over the deposit pins 8 in the contact bank. Also mounted on the supporting shelf 10 is a ratchet wheel 30 20 and a gear wheel 31 which are preferably formed integral with each other. These wheels are rotatably supported on a stud 32, and are held in position by a nut 33. When assembled on its bearing stud 32, the gear 25 wheel 31 is adapted to mesh with teeth 20 on gear member 11. A clock spring 34, one end of which is fastened to ratchet wheel 30, and the other end to shelf 10, acts through gears 31 and 20 to maintain the 30 carriage 17 and its plunger bar 23 in their normal rotary position with respect to the contact bank, as seen in Fig. 1.

Mounted at suitable locations on the shelf 10 of frame 29, as shown in Fig. 1 of the 35 drawing, are the primary, secondary and tertiary operating electromagnets 35, 36 and 37 respectively. Magnet 35 is provided with an armature 38 having a pivoted pawl 39 arranged to engage the long tooth ratchet 40 wheel 30, which operates through gears 31 and 20 to rotate carriage 17 and plunger bar 23 by long steps in a clockwise direction as viewed from the top. Each one of these 45 long steps advances the plunger 24 through an arc corresponding to a numerical group of one hundred trunk intersecting points, or in other words, through an arc comprising ten radial rows of deposit pins 8. Magnet 36 is provided with an armature 40 having 50 a pawl 41 which engages the short tooth ratchet wheel 19 to rotate the plunger bar 23 by short steps in a clockwise direction. Each short step serves to advance plunger 24 through an arc corresponding to the 55 distance between two consecutive radial rows of trunk intersection points. The tertiary magnet 37 is equipped with an armature 42 having a pivoted pawl 43 which is arranged to engage and rotate the ratchet wheel 15. 60 A spring held pawl 44 is pivoted on ratchet wheel 15, and coöperates with gear teeth 13 on member 11 in such a manner that when magnet 27 steps ratchet 15 in a clockwise direction, the pawl 44 engages teeth 13 to im- 65 part a similar rotation to the member 11.

Rotation of gear member 11 operates as above described to advance plunger 24 radially through the distance corresponding to two circular rows of pins 8 for each step of the magnet 37. 70

Coming now to a discussion of the manner in which the plunger 24 is operated to deposit the pin 8 at a selected trunk crossing point there is seen in Fig. 5, a detailed showing of the mechanism for accomplishing this purpose. The boss 21 is provided with two lugs 45 which support a rotatable pivot pin 46. A yoke piece 47 is securely mounted on pin 46, and at its upper end is pivotally attached to the hollow guide and 75 supporting block 48. A plunger operating bar 49 is pivoted at one end to an arm of the bell crank lever 95. The lever 95 is pivotally secured to bar 23 with the other arm thereof extending into operative relation to 80 plunger 24. The plunger operating bar 49 is disposed parallel to bar 23, its free end being guided by and slidably supported in the hollow block 48. By this arrangement the bar 49, which is forced to participate in 85 the thrusting movement of bar 23, slides through the block 48 a distance corresponding to the number of steps taken in the tertiary operation of the mechanism. The bar 49 is provided with a series of notches 50, 90 one for each circular row of pins 8. A spring catch 51 secured to block 48 constantly tends to move upwardly to engage the notches 50. To retain this catch 51 out of engagement with notches 50 during the 95 movement of bar 49 through block 48 there is provided a lever 52 loosely mounted on pivot pin 46, having a projecting finger 53 with a hook thereon arranged to engage the catch 51. A rod 54, which passes loosely up 100 through a central aperture in gear member 11, is loosely pivoted at its upper end in a slotted portion 55 of lever 52. The rod 54 is joined at its lower end to a bell crank member 56. A spring 57 acting between the 105 frame and member 56 serves to hold rod 54 and lever 52 in the lowermost position, thus preventing the spring catch 51 from engaging notches 50. The bell crank member 56 also carries the armature of an electromagnet 58, which magnet when energized forces 110 rod 54 upward to permit catch 51 to engage a notch 50 in bar 49 for a purpose to be more fully explained hereinafter.

A release magnet 59 is provided with an 115 armature 60 which controls a pair of holding dogs 61 and 62. These dogs engage respectively the ratchets 15 and 19 to hold the switch mechanism in its advanced position.

In order to restore to normal a deposited 120 pin 8, and thus disconnect the two trunk circuits concerned, mechanism about to be described is arranged to be operated step by step to pick out the radial row of pins containing the one desired to be restored, and 125 130

then to restore such pin to its normal position. Rotatably mounted on a bearing stud projecting downwardly from supporting shelf 64 is a pair of ratchet wheels 65 and 66 having oppositely disposed ratchet teeth. The ratchet wheel 66 has a pair of depending lugs 71 and 72, in which the rod 73 is rotatably supported. The outer end of rod 73 carries an apron 74 which extends across a complete row of intersections of an outgoing trunk 2 with the ten incoming trunks 1, 1, and normally rests in a horizontal plane just below the lower ends of deposit pins 8. A pin 75 has its lower end pivoted to projection 76 on rod 73, and extends up through the ratchets 66 and 65 to pivotally engage the tail piece 77 of armature 78. A spring 79 normally holds pin 75 and rod 73 in the position shown, but when the magnet 80 is energized to attract armature 78, rod 73 is rotated in its supporting lugs 71 and 72. Rod 73 rotates the apron 74 into engagement with the particular pin 8 that is depressed and restores the same to normal.

Mounted on the under side of shelf 64 are the stepping magnets 67 and 68. Magnet 67 has an armature 69 and pawl 70 adapted to engage ratchet wheel 65 to rotate the rod 73 in a counter-clockwise direction, looking from the bottom, over the contact bank. Magnet 68 likewise has an armature 81 and a pawl 82 arranged to engage ratchet wheel 66 to rotate rod 73 in the opposite direction. A flexible holding dog 83 exerts sufficient pressure upon ratchet 66 to hold rod 73 in proper position while being stepped around in either direction. Arranged on the under side of supporting shelf 64 and insulated therefrom is a circular conducting strip 84, concentrically disposed with respect to the axis of the releasing mechanism. A series of conducting segments 85 are similarly arranged along the arc of a circle in proximity to strip 84, being insulated from each other and from the supporting shelf 64. A pair of brushes 86 and 87, insulatedly mounted on ratchet wheel 65, are arranged so that the former makes engagement with the continuous strip 84, while the latter successively engages the segments 85 during rotation of the deposit pin restoring rod 73. The purpose of these circuit controlling members will be considered hereinafter.

A description of the operation of the switch now remains to be given. Assuming that the switch shown in a selector switch, and that an incoming call has been extended thereto over one of the ten incoming trunk circuits 1, 1, the switch must first be directively operated to pick out the proper numerical group of ten outgoing trunks; secondly, it must automatically hunt and find an idle outgoing trunk in such group; thirdly, it must hunt automatically to find the crossing point of the particular

incoming trunk 1 on which the call appears with the selected outgoing idle trunk 2; and lastly it must then deposit the circuit connecting pin 8 associated with this crossing point. To accomplish these functions, the group selecting series of impulses is sent to primary magnet 35. Magnet 35 operates its stepping pawl 39 to advance ratchet 30 and gear 31 against the tension of spring 34. The gear 31 acting upon gear 20 operates to rotate carriage 17 together with bar 23 and plunger 24 through an arc corresponding to a group of ten outgoing trunks 2, 2 for each impulse sent to magnet 35. It is evident that, if while carriage 17 and toothed bar 23 are thus being rotated in a clockwise direction as seen in Figs. 1 and 2, the gear member 11 remains stationary with respect to the frame of the switch, rotation of the toothed bar 23 about gear teeth 12 will cause said bar to be simultaneously thrust outwardly. This, however, is prevented by spring 28, whose tension opposes the tendency of such a thrusting motion of bar 23 sufficiently to overcome the inertia and friction of the comparatively light member 11, thereby causing said member 11 to rotate and maintain its normal relation with the teeth on bar 23. Rotation of the gear member 11 at this time is also in a clockwise direction, so that the pawl 44 carried on ratchet 15 rides loosely over the teeth 13 on said member 11. The holding dog 62 engaging the ratchet wheel 19 serves to hold the operated parts in advanced position 100 against the spring 34.

An operating circuit is next established for the secondary magnet 36 which engages its pawl 41 with ratchet wheel 19 to advance the same through the distance of one tooth for each energization of said magnet. Each step of ratchet 19 carries the bar 23 and its plunger 24 through an arc corresponding to the distance between two rows of outgoing trunk intersections. This operation continues until the plunger 24 is positioned in radial alignment with an idle outgoing trunk 2 in the selected group, at which time the circuit of magnet 36 may be opened to render the same inactive. The holding dog 62 acts as in the case of the primary motion to retain the adjusted parts in their advanced position against spring 34.

A circuit may now be closed for the tertiary magnet 37, which operates through its pawl 43 to step the ratchet 15 around in a clockwise direction as seen in Fig. 1. The pawl 44, therefore, engages ratchet teeth 13, whereby the gear member 11 is forced to rotate in a similar direction. Since the spring 34, acting through gears 31 and 20 resists with considerable force any rotation of the carriage 17, rotation of the gear 12 consequently operates to slide the plunger bar 23 outwardly against the tension of 130

spring 28. Hence, for each energization of magnet 37, the plunger 24 is advanced along the selected trunk 2 through a distance equal to that between two adjacent deposit pins 8. As soon as the plunger 24 is stepped to a position above the particular deposit pin 8 which is located at the intersection of the selected outgoing idle trunk circuit 2 with the incoming trunk circuit 1 over which 10 the call has been extended the tertiary magnet is rendered ineffective and the selecting operation thus brought to a close.

Lastly, a circuit may be completed for the energization of magnet 58, which upon 15 attracting its armature moves the rod 54 upwardly. The first upward movement of rod 54 rotates the lever 52 on pivot pin 46, and thereby permits catch 51 to drop into the particular notch 50 in bar 49 that corresponds to the adjusted position of plunger 24. As the rod 54 reaches its full upward position it engages and rotates a lever 88. Lever 88 like the lever 47 is securely fastened to pivot pin 46 so that rotation thereof 20 by rod 54 causes a corresponding rotation of lever 47. The lever 47 by rotating carries the supporting block 48 forward slightly and since catch 51 is now engaging a notch 50, the plunger operating bar 49 is simultaneously advanced with the block 48. This 25 movement of bar 49 relative to the bar 23 operates the bell crank lever 95 to press plunger 24 down against the selected deposit pin 8. Pin 8 thereupon causes the springs 3 and 4 to respectively engage springs 5 and 6 to complete the desired connection. The magnet 58 may now be de- 30 energized, whereupon the rod 54 by disengaging lever 88 permits spring 26 to restore plunger 24 and plunger operating bar 49 to normal position.

The switch having thus performed its function, a circuit is immediately established in any suitable manner for the release 45 magnet 59. Magnet 59 operates to withdraw both holding dogs 61 and 62 from engagement with ratchets 15 and 19 respectively. Upon the withdrawal of dog 61 the spring 28 acts to pull the toothed bar 23 50 back through the channel 22 to its normal radial position. The dog 62 being also removed from engagement with ratchet wheel 19, the spring 34 is at the same time operating through gears 31 and 20 to rotate carriage 17 and its associated parts back to 55 their normal rotary position. By such an arrangement a very simple releasing operation is made possible, it not being necessary for the releasing movement to be completed in one direction before it may begin in another direction as is the usual case in directly operated switches. The switch 60 operating mechanism is now restored to its normal position and is again available for 65 setting up other connections.

After the conversation period has expired or if for any other reason it becomes desirable to disable the established connection, the restoring mechanism operates as follows to restore the deposit pin 8 to its normal 70 position. The stepping magnets 67 and 68 may be arranged to operate the restoring rod 73 continuously forth and back over the contact bank, magnet 67 acting first to step the rod to its extreme forward position, and 75 magnet 68 thereupon acting to step it back again. As soon then as it becomes necessary to restore the operated deposit pin 8, a discriminating condition may be placed on the particular conducting segment 85 individual 80 to the trunk circuit 2 with which the operated pin 8 is associated, there being a segment 85 for each of the one hundred outgoing trunks 2. When the brush 87 arrives on this identified segment 85, suitable circuit 85 means may be operated to open the circuit of the magnet 67 or 68 as the case may be. At the same time the magnet 80 is momentarily energized, and by attracting its armature 78 rotates the rod 73. The apron 90 74 is thereby carried into engagement with the deposited pin 8 and the latter is restored to normal. Either the magnet 67 or 68 may now be operated to again start the continuous movement of the restoring mechanism. 95

While in the drawing the switch disclosed illustrates a contact bank in which two-conductor trunks are used, it is apparent that trunks having any suitable number of conductors may be employed without departing 100 from the spirit of the invention.

What is claimed is:

1. In a switch, a contact bank, a plurality of incoming circuits and a plurality of outgoing circuits terminating in said contact bank, a plurality of contact making members, each adapted to establish a connection between one of the incoming and one of the outgoing circuits, a switching mechanism arranged for a plurality of selective movements, means for operating said mechanism to select one of said contact making members, and means for operating the selected contact making member.

2. In a switch, a contact bank, a plurality of incoming circuits and a plurality of outgoing circuits terminating in said contact bank, a plurality of contact-making members each adapted to establish a connection between one of said incoming circuits and one of said outgoing circuits, a switching mechanism arranged for a plurality of selective movements, means for operating said mechanism to select one of said contact-making members, means for operating the selected contact-making members, and means for restoring the switching mechanism to its normal position.

3. In a switch, a contact bank, a plurality of incoming circuits and a plurality of out-

going circuits terminating in said contact bank, a plurality of contact-making members each adapted to establish a connection between one of said incoming circuits and one 5 of said outgoing circuits, a switching mechanism arranged for a plurality of selective movements, means for operating said mechanism to select one of said contact-making members, means for operating the selected 10 contact-making member, and means for restoring the selected contact-making member to its normal position.

4. In a switch, a contact bank, a plurality of incoming circuits and a plurality of 15 outgoing circuits terminating in said contact bank, a plurality of contact-making members each adapted to establish a connection between one of said incoming circuits and one of said outgoing circuits, a switching 20 mechanism arranged for a plurality of selective movements, means for operating said mechanism to select one of said contact-making members, means for operating the selected contact-making member, means for 25 restoring the switching mechanism to its normal position, and means for restoring the selected contact-making member to its normal position.

5. In a switch, a contact bank, a plurality 30 of incoming circuits and a plurality of outgoing circuits appearing in said contact bank, a plurality of contact making members, each adapted to establish a connection between one of the incoming and one of the 35 outgoing circuits, a switching device, means for advancing said device in a plurality of selective movements to select any one of said contact making members, means for operating the selected contact making member, and 40 means for releasing the switching device to normal while said contact making member remains in its operated position.

6. In a switch, a contact tank, a plurality of incoming circuits and a plurality of outgoing 45 circuits terminating in said contact bank, said circuits being arranged such that each incoming circuit has a crossing point with each outgoing circuit, a switching device, means for selectively operating said device in a plurality of directions to select one 50 of said crossing points, and means for establishing a connection between the circuits at the selected crossing point.

7. In a switch, a contact bank, a plurality 55 of incoming circuits and a plurality of outgoing circuits terminating in said contact bank, said circuits being arranged such that each incoming circuit has a crossing point with each outgoing circuit, contact members 60 at each of said crossing points for establishing a connection between an incoming and an outgoing circuit, a switching device, means for advancing said device to select any one of said crossing points, means for 65 operating the contact members at the se-

lected crossing point, and means for restoring said switching device to normal.

8. In a switch, a contact bank, two groups of trunks terminating in said contact bank, said trunks being arranged such that each 70 trunk of one group has a crossing point with each trunk of the other group, contact members at each crossing point for establishing connection between a trunk of one group and a trunk of the other group, a step-by-step operated switching device, means for advancing said switching device to select any one of said contact members, means for operating said device to operate the selected contact member, means for restoring the 80 switching device to normal, and step-by-step actuated means for restoring an operated contact member to normal position.

9. In a switch, a contact bank, a plurality of incoming trunks and a plurality of outgoing trunks terminating in said contact bank, a plurality of contact making members, each adapted to establish a connection between one of the incoming and one of the outgoing circuits, said members being arranged in groups, a switching device, means for advancing said device to select a group, means for advancing said device to select a contact making member in the group, means for operating the selected contact making 90 member, and means for restoring said switching device to normal position.

10. In a switch, a contact bank, a plurality of incoming trunks and a plurality of outgoing trunks terminating in said bank, a 100 plurality of contact making members, each adapted to establish a connection between one of the incoming and one of the outgoing circuits, said members being arranged in groups and subgroups, a switching device, 105 means for advancing said device to select a group, means for advancing said device to select a subgroup, means for advancing said device to select a contact making member in the subgroup, means for operating 110 said member, means for thereupon restoring the switching device to normal, and means for restoring an operated contact making member to its normal position.

11. In a switch, a contact bank, a plurality of incoming trunks and a plurality of outgoing trunks appearing in said bank, a plurality of contact sets, each adapted to establish a connection between one of the incoming and one of the outgoing circuits, 115 said sets being arranged in groups and subgroups, a switching device, means for moving said device in long steps to select a group, means for moving said device in short steps to select a subgroup, means for further moving said device to select a contact set in the subgroup, means for operating 120 said set, and means for then restoring the switching device to its normal position.

12. In a switch, a contact bank, a plurality 130

- of incoming trunks and a plurality of outgoing trunks terminating in said bank, said trunks being arranged such that each incoming trunk has a crossing point with each 5 outgoing trunk, a contact set at each crossing point for connecting an incoming trunk to an outgoing trunk, a deposit pin for operating each contact set, a plunger, means for selectively advancing said plunger to 10 select any one of said deposit pins, means for operating said plunger to operate the selected deposit pin, means for restoring said plunger to its normal position, and means for restoring an operated deposit pin.
- 15 13. In a switch, a contact bank comprising a plurality of sets of spring contacts, said sets of contacts being arranged in groups and subgroups, a switching device arranged to be advanced in a plurality of 20 selective movements to select and operate a desired contact set, and means for restoring said device to normal position while maintaining the contact set operated.
14. In a switch, a contact bank comprising a plurality of sets of spring contacts, a pin associated with each of said contact sets, a plunger, means for advancing said plunger step-by-step in a plurality of selective movements to select a set of contacts, means for 25 operating said plunger to depress the pin associated with the selected set to close the contacts thereof, and means for restoring a depressed pin to its normal position.
15. In a switch, two groups of conductors, 30 said conductors being arranged such that any conductor in one group may be connected to any conductor in the other group, a switching device, means for operating said device in arcuate and radial selective movements to select a desired conductor in each 35 of said groups, means for establishing a connection between the selected conductors, and means for restoring said switching device to normal position.
- 40 45 16. In a switch, a contact bank comprising a plurality of sets of contact members arranged in a plurality of arcuate rows and radial rows, said contact members arranged to lock in their operated positions, a switching mechanism comprising a bar rotatable 45 into operable relation to any of said radial rows individually and movable radially over said radial rows, an operating plunger for said contact member carried by said bar, an electromagnetic step-by-step mechanism for 50 selectively rotating said bar and plunger into alignment with a desired radial row of contact members, a second electromagnetic step-by-step mechanism for selectively moving said bar and plunger radially into operable relation with a desired contact member, means for moving said plunger to operate said contact member, means for restoring said plunger to normal, means for restoring said switch mechanism to its normal 55 position upon completion of an operation, and a common restoring means for said contact members.
17. In a switching mechanism, a row of contact operating members, a bar movable longitudinally over said contact operating members, a plunger on said bar for operating said contact operating members individually, an operating bar for said plunger arranged parallel with said first-mentioned 60 bar and movable therewith, means for moving said first-mentioned bar radially to position said plunger into operable relation with a contact operating member, means operable to move said operating bar to effect 65 operation of said plunger, said last-mentioned means being operable when said plunger is in any of its operable positions.
18. In a switching mechanism, a plurality of rows of contact operating members, 70 means for operating said contact operating members individually, a restoring device for said contact operating members comprising a rod, an apron on said rod, said rod movable into operable relation to any of said 75 rows of contact members individually, means for moving said rod into operable relation to a row of contact members, and means for rotating said rod to effect a movement of said apron to restore an operated 80 contact member to normal.
- In witness whereof I hereunto subscribe my name this 8th day of May, A. D. 1918.

JAMES L. MCQUARRIE.
